Platt Iron Works, Inc., Dayton, Ohio, a cor-
poration of New York

Application May 27, 1935, Serial No. 23,672

25 Claims. (Cl. 197—84)

This invention relates to imprinting apparatus, and more particularly to apparatus for imprinting characters in justified lines.

One of the principal objects of the invention 5 is the provision of justifying apparatus that is simple in construction, is effective in operation, and which will accurately reproduce unjustified copy to lines of justified length within a wide range of line lengths.

10 Another object of the invention is the provision of justifying apparatus that is arranged to readily receive a standard typewriter or the like in operating assembly therewith, in which an operating connection is afforded directly with the typewriter key bars and is rendered operable by the attachment of the typewriter to the justifying device.

15 A further object of the invention is the provision of justifying apparatus comprising a compact assembly readily attachable to a standard typewriter or the like and having a shallow horizontally extending typewriter supporting frame portion which affords a key positioning closely approximating that of a normal typewriter mounting, and a comparatively narrow vertically extending frame portion that carries the spacing mechanism of the justifying device in a position closely adjacent the rear of the typewriter.

20 Other objects and advantages of the invention 20 will be apparent from the following description, the accompanying drawings and the appended claims.

25 In the drawings, which illustrate a preferred embodiment of the invention,—

Fig. 1 is a side elevational view of the justifying device and a typewriter in operating assembly;

Fig. 2 is a perspective view of the operating member that is engaged by the typewriter key bars and which serves to actuate the justifying device;

Fig. 3 is an elevational view of the justifying device alone with the front portion removed for clearness of illustration; the view being taken as indicated by the line 3—3 of Fig. 1;

Fig. 4 is a fragmentary sectional view of the unjustified copy carrier as indicated by the line 4—4 of Fig. 3;

Fig. 5 is a fragmentary vertical section as indicated at 5—5 of Fig. 3 and shows the details of one of the pointers for the unjustified copy;

Fig. 6 is a view in perspective of the reciprocal frame of the justifying device;

Fig. 7 is a horizontal section as indicated at 7—7 of Fig. 1;

Fig. 8 is a vertical section as indicated by the line 8—8 of Fig. 3; and

Fig. 9 is a vertical sectional view as indicated by the line 9—9 of Fig. 7.

The justifying device of the present invention 5 is of such character that it may be built into a typewriter or the like as an integral part thereof, but in accordance with the preferred embodiment, and as illustrated, it is a separate structure to which an existing complete typewriter 10 may be assembled. In the illustrated embodiment of the invention, in which like characters of reference designate like parts throughout the several views thereof, the justifying device is shown as comprising a frame 10 having a shallow 15 horizontally extending portion 11 that is arranged to receive a typewriter thereon in a predetermined position of assembly. The frame portion 11 has typewriter attaching means in the form of extending lugs 12 for the reception of 20 screws 13 that threadedly engage the typewriter in the screw holes which normally serve for the attachment of the typewriter feet. The usual typewriter feet, however, are removed, and as the justifier frame portion 11 is quite shallow, the 25 operating position of the typewriter when assembled on the justifier is such that the elevation of the keys differs but slightly from the key position when the typewriter rests on a table in the normal manner. The typewriter attaching 30 means, in this instance the lugs 12, are of such construction as to permit a range of adjustment or to permit ready replacement so that any one of a number of standard typewriting machines 35 may be readily accommodated on the frame.

Extending upwardly from the rear of the horizontally extending frame portion 11 and rigid or integral therewith is a vertically extending frame portion 15 having provision for support of the justifying mechanism, which is indicated generally by the numeral 16, and for support of an unjustified copy carrier 17. The frame portion 15 is quite narrow and lies closely adjacent the rear of the typewriter.

The justifying device incorporates an operating connection to the typewriter key bars, and a driving connection to the typewriter carriage 18 for control of movement thereof. In the justifying device, operatively interconnected between the operating connection and the driving connection, are adjustably variable spacing means. The spacing means incorporates adjustments to compensate for various line shortages and to produce lines justified to a desired one of a plurality of line lengths. Having made the required ad- 45

50

55

55

justments, actuation of the operating connection, working through the adjusted spacing means, moves the driving connection and connected typewriter carriage in desired amounts.

Both the operating connection to the key bars and the driving connection to the typewriter carriage are of such character that they are readily made upon assembly of a typewriting machine to the frame. The operating connection is arranged as a rockable bail 20 which lies within the horizontal frame portion 11 and extends across it beneath the typewriter key bars which are indicated generally by the numeral 21. As shown, the rockable bail 20 comprises parallel side rails 22 which extend upwardly at their forward ends and are joined to a cross rail 23 which, in the normal position of the rocking member, lies directly beneath the key bars and is of sufficient length transversely of the typewriting machine to underlie all of the keys which have to do with a spacing movement, that is, all of the spacing or character keys. The bail 20 is supported on a pivot shaft 24 carried by the frame 11 and extending through aligned openings 25 in the side rails 22. Toward the rear of the machine the side rails are bent inwardly toward one another and are together bent to the rear to form a rearwardly projecting arm 26 to which a link 27 is pivotally attached by engagement in an opening 28 formed adjacent the end of the arm 26. A spring 30 serves to urge the rockable bail upwardly toward its normal position.

The cross rail 23 lies closely adjacent the key bars so that upon actuation of any one of the named keys the bail 20 is engaged thereby and is caused to rock and thus impart an upward movement to the link 27 which has an operating connection to an escapement mechanism on the justifying device. The escapement, which may be of any suitable character, is shown to be of that type which is well known in the art and comprises a star wheel to which step-by-step movement is imparted by movement of a rock member. In the present instance the rock member is actuated by movement of the bail 20. As shown, the link 27 is adjustably connected to a vertically slideable block 33 having an inclined forward face 34 that is engaged by the lower portion of the spring pressed rock member 35 that serves as the escapement release and controls movement of the escapement star wheel 36. Reciprocating movement of the link 27 rocks the member 35 to release the escapement wheel 36 for movement by the amount of one space step. A pinion 38 is connected to the star wheel and is in turn engaged by a rack 39 that is supported from the justifying mechanism. The usual overrunning clutch is provided between the star wheel and the pinion so that free rack movement may occur in one direction while movement in the opposite or feeding direction is under control of the escapement.

The rack 39, as shown, is supported from a rockable U-shaped member 40 of which the parallel end portions 41 (Fig. 7) are pivotally mounted at 42 on forwardly projecting blocks 43 that are fixed to a plate 44. The plate 44 is mounted for sliding movement in the direction of rack travel upon a member 45 that is shown as a vertically extending plate and which, for simplicity in description, is referred to as the justifier carriage. As shown, the carriage 45 has laterally spaced forwardly extending bosses 46 which threadedly receive shoulder screws 47 that pass through laterally spaced horizontally extending slots 48 in the

plate 44. The plate is closely held except for free sliding movement in the direction of the slots.

The justifier carriage 45 is supported upon the frame portion 15 for reciprocating movement in the direction of rack travel. As shown, the carriage 45 has horizontally extending V rails adjacent the upper and lower edges thereof as indicated at 50 and 51. The frame 15 has V rails 50' and 51' facing oppositely to the carriage rails and spaced therefrom an amount sufficient to receive bearing balls therebetween. A plurality of balls 52 are positioned between the rails of each of the rail pairs and are maintained in properly spaced relationship by the provision of suitable spacing means. The bearing balls are spaced by being loosely mounted within star wheels 53 turning on vertical axes of which the teeth engage the teeth of racks positioned on the opposite sides of each of the related rail pairs. The racks extend vertically, are laterally spaced and are positioned so that the teeth overlap in the plane of travel of the star wheels 53. As shown, the rearward sides of the carriage rails 50 and 51 have racks 54 while the forward sides of the frame rails 50' and 51' have racks 54' attached thereto as indicated in Fig. 1. The proportioning of the pitch diameter of the star wheels, the diameter of the bearing balls and the arrangement of the rail grooves are such that free rolling movement is afforded while preventing the bearing balls from moving from their properly related positions.

It is the controlled relative movement between the rack supporting plate 44 and the justifier carriage 45 that affords the space change necessary in the stepped movement of the typewriter carriage to provide justified writing, and mechanism is interposed between the plate and carriage and connecting these parts so the desired controlled movement may obtain. In order that the stepped movement of the movable parts mentioned above will be under the control of the escapement they are spring tensioned so that they are constantly urged toward the left (as viewed in Fig. 3) which is toward the right hand margin of writing. As shown, a spring tensioned spool 56, well known in the typewriter art for this purpose, carries a tape 57 that connects at 58 to the carriage 45 to provide the desired tension through the justifying parts, the plate 44 and rack 39, and the intermeshed pinion 38 through the one way clutch to the star wheel 36 which is thus held against the rock member and therefore may move to release the parts only upon actuation of the rock member 35 by operation of the typewriter keys.

Before describing the justifying parts the description will continue with reference to the driving connection to the typewriter carriage 19 mentioned briefly above as being of such character that the connection is readily made upon applying a typewriter to the justifying device. As shown, the justifier carriage 45 has a forwardly projecting arm 60 (Figs. 1 and 7) which terminates in a readily replaceable cross bar 61 having a plurality of notches 62 therein. The typewriter carriage is provided with a lug 63 which may be selectively engaged in the desired notch of the bar 61. As shown, the engaging lug 63 is fixed to a rotatable shaft 64 that is mounted on bearing blocks 65 that are attached to the typewriter carriage as, for example, by being fixed to the tabulating bar. The lug 63 is urged toward engaging position by provision of a spring 67, and may be released by depressing the finger piece 68. The notch side

walls are inclined slightly toward one another. This, coupled with the spring tensioning of the lug, provides a driving interconnection that serves to hold the justifier carriage and typewriter carriage in accurately maintained operating alignment. The driving connection described is such that carriage shift is accommodated. The interfit of the lug 63 with the bar notches is on a vertical line so that vertical movement of the typewriter carriage, as when writing capitals, is accompanied by a sliding movement of the lug 63 in the engaged notch. The related spacing of the notches will be discussed in greater detail below and is taken up at this time merely to point out the driving connection between the justifier and the typewriter.

Referring now to the justifying mechanism, the plate 44 and carriage 45 are interconnected and relatively moved each time a key is struck by a member which is controlled or guided by an adjustably variable member. As shown the interconnecting member is constructed as a bell crank 70 having its central portion pivotally mounted for rocking movement upon a stud 71 that is fixed to and projects from the carriage 45. One end of the bell crank 70 is pivotally connected to a stud 72 that is fixed to and projects rearwardly from the plate 44; the stud 72 passing through a clearance opening 73 in the carriage 45. Although the movement of the stud 72 is in a straight line while the bell crank end to which it connects moves in a curved path about the pivot center 71 the angular travel of these parts is so small that binding does not occur although the parts are closely held. The opposite end 75 of the bell crank has a laterally projecting stud 76 that rotatably carries a roller 77. The roller engages the adjustably variable member 80 which is shown as comprising a track including spaced parallel rails 81 that are joined adjacent one end by connection to a block 82 which in turn is pivotally connected at 83 to a bracket 84 fixed to a cross brace 85 of the frame portion 15. The opposite ends of the spaced rails are joined by a connecting bar 87. The bar 87 and block 82 serve to accurately space the rails apart such a distance that the bell crank roller 77 is closely received therebetween and, although it is freely slidable therein, no lost motion may occur.

The bell crank moves with the justifier carriage and in moving traverses the member 80. If this member 80 lies parallel to the direction of carriage movement no rocking movement of the bell crank will occur, and plate 44 and carriage 45 will move the same amount when a key is depressed. If the member 80 is inclined the bell crank is caused to rock upon the pivot 71 and thus causes relative movement between the rack supporting plate 44 and the justifier carriage 45 during traverse of these parts. This relative movement is the justifying increment and modifies the normal movement of the typewriter carriage produced by actuation of the escapement. In the illustrated embodiment of the invention the track 80 is inclined upwardly from a normal horizontal position and when so moved increases the length of the character space steps accordingly. It is pointed out that the track may, if desired, have a downward inclination in which case the character spaces would be shortened when justifying so that the justified line length would then be something less than the longest unjustified line.

To provide for accurate movement of the parts in response to a predetermined positioning of the track member 80 the pivot axis 83, upon which the member rocks, is midway between the adjacent

faces of the spaced rails and therefore lies in the plane traversed by the bell crank stud axis 76 in moving along the member 80. To provide for an aligned left hand margin, which is the position for adjustment of the parts, the parts are so assembled that in the left hand margin position the pivot axis 83 and the stud axis 76 coincide so that the member 80 may be rocked without imparting movement to the bell crank and therefore to the carriage 45 that moves in response to bell crank movement. As will be apparent from Fig. 9, the block 82 has a clearance gap 90 for passage of the roller carrying stud 76. As is shown in Fig. 3, the included angular swing of the arm 75 of the bell crank 70, as defined by the lines 190 and 191, is equally divided on opposite sides of the line 192 defining the direction of movement of the justifier carriage parts.

Adjusting means are provided for the member 80 to establish a positioning that compensates for line shortage and is coordinated to the selected one of a plurality of justified line lengths. As shown, a vertically reciprocable frame 91 stands within the supporting frame portion 15 and comprises side rails 92 having spaced slots 93 for reception of screws 94 that engage the frame 15 to slidably guide the frame 91 for rectilinear movement. The side rails are interconnected by cross members which, as shown, comprise a lower rod 96 and an upper bar 97. The upper bar is preferably of rectangular cross section. It is calibrated in steps of normal character spacing across the front face as indicated at 98 and is correspondingly notched along the lower edge as indicated at 99. The rod and bar serve as supports for a member 100 that is slidable thereon and which has an operating connection to the adjustably variable track member 80. As shown, the member 100 comprises a plate like part which is formed at its upper end to overlie the bar 97 as indicated at 102, and is formed at its lower end into two arms that separately encircle the rod 96 as indicated at 103. The upper part has latch means to engage the bar and, as shown, this comprises a spring pressed detent 105 that engages the notches 99. An indicating pointer 106 is affixed to the member 100 and registers with the calibrated scale of the bar 97.

The member 100 has a depending plate 110 fixed to the lower part thereof, which pivotally carries a block 111 that engages the adjustably variable space controlling member 80. As shown, the block 111 is substantially U shaped of which the parallel arms 112 are cut away or notched as indicated at 113 to receive the opposing faces of the spaced rails 81 of the member 80. The pivotal mounting of the block, indicated at 114, is such that the axis of movement is midway between the rails 81 and therefore lies in the plane traversed by the bell crank arm pivot 76 as does the pivot axis 83 upon which the member 80 rocks. The engagement of the block 111 with the track member 80 is such that the block may freely move along the track but without lost motion.

For adjusting the positioning of the member 80 to afford a desired length of character space the entire reciprocable frame 91 is bodily movable under the control of an adjusting knob 116 which is accessible at the front of the machine 70 and which is fixed to a rotatable shaft 117 extending toward the rear of the machine and having fixed thereto a pinion 118 that meshes with a rack 119 that is fixed to the lower end of the right hand rail 92 as indicated in Figs. 3 and 6.

The two rails 92, which are the side members of the frame 91, move in unison by being interconnected by the cross members 96 and 97, and they are additionally held in proper relationship by a rack and pinion interconnection. As shown, each rail 92 has a rack portion 122. A cross shaft 123, rotatable in the frame 15, has fixed adjacent each end a pinion 124 that engages the corresponding rack 122 and thus affords additional bracing against deformation of the frame. An extension on the cross shaft 123, continuing beyond the frame 15, carries a notched segment 126 that serves as a stop means defining dwell points in frame movement. As shown, the segment 126 has an annular rim portion on which a plurality of notches 127 occupy a portion of the periphery thereof. A spring pressed detent 128 is provided to engage the notches and thus hold the frame and associated parts in desired predetermined positioning, and a limit stop pin 130 is provided that is engageable with spaced shoulders 131 of the segment to limit movement to within the limits of adjustment.

The notch spacing is such as to provide dwell or stop positions for the frame 91 differing from one another by an amount sufficient to provide one character space justification in a line, for each notch. That is, each step movement of the frame alters the angular adjustment of the member 80 by an amount such that the carriage will traverse a given line length in one less character step or space. It is apparent that when the member 80 stands horizontal or parallel to the direction of carriage movement, there will be no rocking movement of the bell crank and consequently no movement between the rack supporting plate 44 and the bell crank controlled carriage 45. It will now be apparent that vertical displacement of the frame 91 controls the amount of total justification produced in a line, and that this amount of justification is not a function of the line length. That is, a line three inches long and three character spaces short of justified line length will require the same amount of justification as a line eight inches long that is three characters short. As shown, the segment has sufficient notches to justify lines as many as six characters short of justified length. Practice has proven that this is a sufficient range of adjustment. It is believed clear that this range may be readily increased if desired.

The amount of justification per character space in a given length line is a function of the justified line length and varies with the line length. That is, the space change or increment per space required to absorb a three character space shortage in a three inch line is considerably greater (per character space) than in an eight inch line. This is compensated for by adjustment of the transversely movable member 100 which is properly positioned by reference to the calibrated scale associated with it. The scale is calibrated in character steps of normal length, that is, steps or spaces of a length to which no justifying increment is added. For convenience the calibration is set off by inches of line length with the zero graduation corresponding to the left hand margin position of writing. Therefore, having selected the desired justified line length to which copy is to be written, it is only necessary to bring the pointer of the member 100 into registration with the proper graduation of the calibrated scale to obtain a shortage distribution for the selected line length.

To briefly review, to adjust the device the

member 100 is moved to a position corresponding to the line length as indicated on the calibrated scale. The frame 91 is then moved by steps an amount sufficient to absorb the line shortage. It is to be noted here that the movement of the frame and the movement of the member 100 on the frame is in each instance a straight line movement and both are in a common plane. Further, the movements of the adjustable track 80, the justifying bell crank 70, the frame 91 and member 100 all are in parallel vertical planes; the parts being closely related and occupying but a relative short fore and aft space at the rear of the typewriter. Frame positioning is readily determined by provision of an indicator that registers with a graduated scale that is calibrated in terms of character space shortage. As shown, (Figs. 3 and 6) the right hand rail 92 of the frame 91 has, adjacent the upper end thereof a bracket 133 terminating in a pointer 134 that is adapted to register with graduations 135 provided on the frame portion 15 and spaced according to the movement of the frame from one notch position of the segment to the next adjacent; this movement, as mentioned above, amounting to one character space of justification per step.

The establishing of the frame positioning or adjustment of the member 80 is further greatly simplified by provision of a carrier for supporting unjustified copy in view of the operator, and provision of indicating means associated with the frame and movable into registration with the end of a line of unjustified copy on the copy carrier, as an index of the positioning of the frame that will afford a spacing such that the indicated line will be reproduced to justified length.

As shown, the unjustified copy carrier 17 comprises a roll 138 freely rotatable in the frame portion 15 and has an operating knob 140 accessible at the end thereof. A releasable guide chute 141 is provided for directing copy sheets around the roll, and additional guide means in the form of rollers 142 are mounted on the chute for support of the copy. The chute is shown supported on resilient fingers 143 that are attached to the frame 15 as shown at 144. These fingers are tensioned to urge the chute and rollers toward engagement with the roll 138. The chute and rollers may be moved to release position by actuation of the finger piece 146 which is shown fixed to a shaft 147 extending across the frame and rockable therein. The shaft has cam members 150 positioned to engage the resilient fingers. These cam members are shaped so that when moved from a disengaged position they first engage in a manner that the tensioned fingers tend to release them so that upon release of the finger piece the cams will be forced to disengaged position. Further engaging movement brings the cam flats 151 into contact with the fingers to hold the chute disengaged when it is desired to adjust the copy therein. Such an arrangement permits the unjustified copy to be accurately held for indication of adjusted setting of the machine by registration of pointers that are associated with the copy carrier and are connected to the frame 15.

As shown, a cross bar 154 has slotted engagement at 156 with screws 157 in the frame 15. The length of the slots 156 is sufficient to permit bar movement to the extent of the total justifying range, or the maximum length of line shortage. Adjustably mounted on the bar is a pair of pointers 158; two being provided for use where double column matter is to be typed. As shown, 75

each pointer comprises a block 160 that is grooved at 161 to be slidably received on the bar. Holding means are provided at one edge of the bar by a plate 162 overlying the bar and attached to the block by screws 163. The opposite edge of the bar is similarly held by a pointer 164 having an overlying part 165 and an extending end 166 projecting toward the copy carrier. A thumb screw 167 threadedly engages the block and is adapted to bear against the bar to hold the pointer in desired position. Interconnection of the bar 154 with the frame 91 is by means of a bell crank 169 which is pivotally mounted at 170 on a bracket 171 extending from the frame 15. One end of the bell crank connects at 172 to the bar and the other end connects to a stud 173 on the frame bracket 133 that carries the indicator 134. Movement of the frame 91 is thus communicated to the cross bar 154.

20 To refer now to the operation of the device, when it is desired to produce copy written in justified lines the copy to be so prepared is first written in lines of random length in which all character spaces are uniform and correspond to the normal spacing of the machine. The unjustified copy is then placed in the copy carrier 17 and the first line to be written is brought into view and in registration with the line of travel of the pointers 166. The adjustment knob 116 is then actuated to bring the frame 91 to the position of no justification wherein the adjustable member 80 stands horizontally so that the machine will write at normal character spacing. If single column matter is to be written only the right hand pointer 166 need be adjusted and this is then affixed to the bar 154 in a position corresponding to the right hand margin of a line of justified length as measured from the left hand margin of the unjustified copy. To facilitate adjustment of the machine a designating mark may be placed on the unjustified copy at the time it is prepared; this mark defining the justified line length with respect to the left hand margin of the copy and affording a convenient means of locating the pointer 166 upon placing the copy in the carrier. The member 100 is then moved to a position corresponding to the justified line length as defined by the calibrated scale on the bar 97. Subsequent movement of the knob 116 to move the frame 91 and member 80 to a position as defined by registration of the pointer 166 with the end of the unjustified line to be copied will establish a setting of the machine such that the indicated unjustified line will, upon being rewritten, be reproduced to justified line length.

55 Regardless of the position that the unjustified copy is to occupy on the sheet when reproduced in justified lines, the writing operation begins at the left hand margin position of the device wherein the bell crank pivot axis 16 and the pivot axis 83 of the member 80 coincide. This is done so that all subsequent lines will have a common starting point such that a spacing adjustment may be made without imparting movement to the justifier carriage as explained above. As a result the line left hand margins are vertically aligned on the sheet. The justified copy, which is produced on the typewriter platen 175, may occupy any position within the limits of the platen, that is, the sheet upon which this is to be written may be placed to the right or to the left as desired so that the margin of typing will occur a desired distance from the edge of the sheet. If several different line lengths are to occupy the same sheet such a situation is provided for either

by changing the adjustment of the member 100 to the proper line length wherein the left hand margins will continue to be aligned or, if it is desired to indent the left hand margins, this may be accomplished by making the above adjustment and then re-engaging the driving connection latch 63 in the desired one of the notches 62 to move the typewriter carriage with respect to the justifier carriage. In the illustrated embodiment of the invention, the bar 61 containing the notches 62 shows a notch spacing amounting to $\frac{1}{2}$ " between the right hand hand group of indenting notches so that different groups of lines may be indented in steps of $\frac{1}{2}$ ". If desired, other bars 61 may be substituted having a different and desired notch spacing.

When the machine is to be used for double column writing wherein two laterally related columns are written, both of which are justified, both pointers 166 are used and are spaced apart according to the margin spacing of the copy as defined by the distance of the double column notches on the bar 61. As shown, the bar 61 (Fig. 7) is provided with a series of margin indenting notches adjacent its right hand end and has two additional notches 176 adjacent the left hand end. When using the machine for double column work, and after having established the positioning of the pointers 166, the machine is justified for writing the left hand column of the first line by bringing the left hand pointer into registration with that column line end. This is done with the driving connection engaging the extreme right hand notch. The left hand column is written after which the machine is brought back to the left hand margin position and the typewriter carriage is then moved independently of the justifier carriage for engagement of the driving latch 63 with the proper column notch 176. Adjustment is then made to bring the right hand pointer into registration with the end of the right hand column of line 1 of the unjustified copy after which this column line is then reproduced. Here also a wide range of column spacing may be provided for by substituting different bars having a desired column notch spacing.

In order that the machine may be rapidly traversed in the direction of feeding movement the rack 39 is arranged so that it may be readily lifted from engagement with the escapement pinion 38. As shown, the right hand block 43 pivotally carries a finger piece 180 having an extending inturned portion 181 that underlies the rack supporting member 40 and which, upon a clockwise movement of the finger piece, causes the rack to be lifted against the tension of springs 182 that engage the ends 41 of the U-shaped rack supporting member and urge the rack toward engaging position. As explained above, traversing movement in the direction opposite to that in which the carriage feeds is obtained by arranging the pinion 38 with a one way drive or overrunning clutch. Regardless of the direction of traversing movement justification obtains because the justifying increment occurs between the rack supporting member 44 and the justifier carriage 45.

As the justifying device is used in conjunction with a typewriting device, either by being constructed as an integral part thereof or by being arranged as an attached assembly as illustrated, and as typewriting devices have margin stops to limit carriage travel, it is unnecessary to provide the usual margin stops in the justifying

device. It does, however, have a safety stop that is effective between the line length slidably adjustable member 108 and the justifier carriage 45 to limit the justifying travel to amounts within the limits of the machine. As shown, the 5 slideable member 108 which is adjustably positioned by a notched interfitting engagement with the rail 87, has a forwardly projecting lug 185 that is positioned to engage a rearwardly projecting lug 186 on the carriage 45. The relative 10 positioning of these lugs is such that they engage when the carriage is moved a slight distance, say one or two spaces, beyond the distance established by the justified line length setting 15 of the device, which is to say beyond the justified line right hand margin position. This stop is primarily effective on short lines having maximum justification where the justified movement per space step is a maximum and where, if the 20 carriage travel greatly exceeds the normal stopping point, damage may result from the moving parts of the device reaching limits of travel such, for example, as the screws 47 of the justifier carriage binding in the ends of the slots 48, or 25 similar binding on the pointer bar 154 upon unrestrained travel such that the screws 157 reach the ends of the slots 158.

It is pointed out that a typewriter when assembled to the justifier may be used with or without the justifying mechanism as desired. When used with the justifying mechanism the typewriter escapement is rendered inoperative so that the typewriter carriage movement is under control of the justifying mechanism of the justifier unit and is actuated in accordance with the operation of the justifier escapement and adjusted setting. When so used the typewriter escapement may be readily rendered inoperative by merely providing a latch that will hold the typewriter escapement rack bar in disengaged position. When the typewriter is to be used in the normal manner it may be so operated through the justifying mechanism with the adjustments set to a position of no justification (with the adjusting member 88 in horizontal position) or it may be operated from its own escapement upon rendering the driving connection to the justifier inoperative. This is accomplished by disengaging the latch 68 from the typewriter carriage to the justifier carriage. No change is required in the operating connection because in no instance is there a positive drive connection between the typewriter and the justifier; it having been pointed out above that the operating connection exists by arranging the operating member so that it underlies the keys and stands closely adjacent thereto so that it is actuated upon depression of any key and without being directly linked thereto.

60 It is thought that it will now be clearly apparent that the justifying device of this invention is such that an existing typewriter may be readily applied thereto with substantially no changes to the standard typewriter and that when so assembled it is as convenient to use as when in its normal position of use. Further, the typewriter when so arranged is capable of producing justified lines within a wide range of length variation differing from one another by only one space length. In addition, the arrangement of the device is such that lines of different length may be readily produced on a single sheet with the margins aligned or indented as desired.

75 While the form of apparatus herein described constitutes a preferred embodiment of the inven-

tion, it is to be understood that the invention is not limited to this precise form of apparatus, and that changes may be made therein without departing from the scope of the invention which is defined in the appended claims.

What is claimed is:

1. A justifying device operable to different justified line lengths and comprising a movable platen, means for moving the platen by character space steps, adjustably variable means for varying the length of a character space step and pivotally movable on a fixed mounting to a desired one of a plurality of positions having co-ordinated relationship to the unjustified line shortage and to the justified line length, positioning means engaging the variable spacing means and movable in a rectilinear path of travel for the line shortage adjustment and in a transverse rectilinear path for the line length adjustment, and means for selectively attaching the 10 platen to the platen moving means at a desired one of a plurality of positions spaced in the direction of platen movement.

2. A justifying device operable to different line lengths and comprising a movable platen, means 25 for moving the platen in character space steps, an angularly adjustable member pivotally movable in a plane and on a fixed axis for varying the length of a character space step and movable to a desired one of a plurality of positions 30 having co-ordinated relationship to the unjustified line shortage and the justified line length, positioning means engaging the angularly adjustable member and movable in a plurality of paths in a single plane parallel to the plane of 35 movement of said angularly adjustable member, said positioning means being movable in one path to afford adjustment for line shortage and movable in a transverse path to afford adjustment 40 for line length, and means for selectively attaching the platen to the platen moving means at a desired one of a plurality of positions spaced in the direction of platen movement.

3. A justifying device operable to different line lengths and comprising a movable platen, means 45 for moving the platen in character space steps, an angularly adjustable member movable to a desired one of a plurality of positions having co-ordinated relationship to the unjustified line shortage and the justified line length, and positioning means for the angularly adjustable member comprising a reciprocable frame, guide means carrying the frame for rectilinear movement to positions of adjustment for line shortage, means guided by the frame for rectilinear movement having operating attachment to the angularly adjustable member for adjusting the same in accordance with movement of said frame and movable on the frame transversely to the direction of frame movement for adjusting said angularly adjustable member for a desired line length.

4. A justifying device operable to different line lengths and comprising a movable platen, means for moving the platen in character space steps, an angularly adjustable member extending transversely of the device and movable in a plane parallel to the direction of movement of the platen to a desired one of a plurality of positions having co-ordinated relationship to the unjustified line shortage and the justified line length, 70 positioning means for the angularly adjustable member having paths of travel parallel the plane of movement of the angularly adjustable member comprising a vertically reciprocable frame, guide means carrying the frame for rectilinear 75

movement to positions of adjustment for line shortage, means guided by the frame for rectilinear movement having operating attachment to the angularly adjustable member for adjusting the same in accordance with vertical movement of said frame and movable on the frame transversely to the direction of frame movement for adjusting said angularly adjustable member for a desired line length.

5 5. A justifying device operable to different line lengths and comprising a movable platen, means for moving the platen in character space steps, adjustably variable means for varying the length of a character space step comprising a movable 10 member pivotally supported on a fixed mounting and movable to a desired one of a plurality of positions having coordinated relationship to the unjustified line shortage and the justified line length, and positioning means for the adjustably variable means comprising a vertically reciprocable frame 15 having laterally spaced vertically extending side members, a rack on each of said side members, a cross shaft, pinions fixed to said cross shaft and engaging each of said racks and affording an operating interconnection of the side members for movement thereof in unison, and a control shaft having an operating knob thereon for adjustment of the frame to compensate for line shortage, and means adjustably mounted on the frame and movable transversely of the side members to a position of adjustment compensating for line length, said adjustably mounted means having an operating connection to said adjustably variable means.

20 6. A justifying device operable to different line lengths and comprising a movable platen, means selectively engageable with the platen at a desired one of a plurality of positions spaced in the direction of platen movement and adapted to move the platen by character space steps, adjustably variable means for varying the length of the character space step and movable to a desired one of a plurality of positions having coordinated relationship to the unjustified line shortage and to the justified line length, and 25 positioning means for the adjustably variable means comprising a rectilinearly movable frame adjustable to a positioning coordinated to the line shortage, a transverse cross rail on said frame, a member adjustably movable on said cross rail, said cross rail being calibrated by character spaces in terms of justified line length and having positioning notches corresponding to the calibrations thereon, means on the adjustably movable member engageable with the rail notches as a means of positioning the member on said rail, said adjustably movable member operatively engaging said adjustably variable means for operating the same.

30 7. A justifying device operable to different line lengths and comprising a movable platen, means for moving the platen by character space steps, adjustably variable means comprising a pivotally supported track for varying the length of a character space step and movable to a desired one of a plurality of positions having coordinated relationship to the unjustified line shortage and the justified line length, said track comprising spaced parallel rails, means operatively connecting the track and platen having engagement with adjacent faces of the spaced rails, and positioning means for the track comprising a frame movable in a straight path to different predetermined positions coordinated with the amount of line shortage, transverse guide means on said frame, slidable means adjustably slidable on the

guide means to positions coordinated to the desired justified line length, and a positive pivotal connection between said slidable means and track, said pivotal connection being movable along the track and having engagement with the opposite faces of the spaced rails.

5 8. A justifying device operable to different line lengths and comprising a movable platen, means for moving the platen by character space steps, adjustably variable means for varying the length of the character space step and movable to a desired one of a plurality of positions having coordinated relationship to the unjustified line shortage and to the justified line length, and positioning means for the adjustably variable means comprising a vertically reciprocable frame having laterally spaced vertically extending side members, a rack on each of said side members, a cross shaft, pinions fixed to said cross shaft and engaging each of said racks and affording an operating interconnection of the side members for movement thereof in unison, and a control shaft having an operating knob thereon for adjustment of the frame to compensate for line shortage, and means adjustably mounted on the frame and movable transversely of the side members to a position of adjustment compensating for line length, said adjustably mounted means having an operating connection to said adjustably variable means.

20 9. A justifying device operable to different line lengths attachable to a typewriter having a movable platen and movable key bars, said device comprising a frame having attaching means for affixing a typewriter thereto, an escapement, means movable in character space steps by actuation of said escapement, means for varying the extent of a character space step movement of said movable means, means on the frame movable directly by any of the typewriter key bars to operate said escapement, and a driving connection on the movable means attachable to the typewriter platen for controlling movement thereof.

25 10. A justifying device operable to different line lengths attachable to a typewriter having a movable platen and movable key bars, said device comprising a frame having a horizontally extending portion provided with attaching means for affixing a typewriter thereto, an escapement, means movable in character space steps by actuation of said escapement, means for varying the extent of a character space step movement of said movable means, means rockably mounted on the frame underlying the typewriter key bars and operated by the typewriter key bars upon actuation thereof to operate the escapement, and a driving connection on the movable means attachable to the typewriter platen.

30 11. A justifying device operable to different line lengths and attachable to a typewriter having a movable platen and movable key bars, said device comprising a frame having a horizontally extending portion with attaching means thereon for fixedly mounting a typewriter, a frame portion extending upwardly from the rear of the horizontally extending frame portion, an adjustably variable spacing means movable by character space steps and carried by said upwardly extending portion, means movably mounted on the horizontally extending frame portion for operating said spacing means and positioned for actuation by direct engagement of the key bars upon movement thereof, and a

- driving connection from the spacing means to the typewriter platen.
12. A justifying device operable to different line lengths and attachable to a typewriter having a movable platen and movable key bars, said device comprising a frame having a shallow horizontally extending portion with attaching means thereon for reception of a typewriter by a vertical downward movement thereon, a frame portion extending upwardly from the rear of the horizontally extending frame portion, said upwardly extending frame portion lying closely adjacent the rear part of an attached typewriter, adjustably variable spacing means movable by character space steps and carried by said upwardly extending portion, positioning means for the variable spacing means comprising a member movably supported on the upwardly extending frame portion and having planar movement in transverse paths of travel, one path of travel establishing positions of adjustment to compensate for line shortage and the other path of travel providing positions of adjustment coordinated to the justified line length, means movably mounted on the horizontally extending frame portion for operating said spacing means and positioned beneath the key bars for actuation by engagement of the key bars upon movement thereof, and a driving connection from the spacing means to the typewriter platen.
13. A justifying device operable to different line lengths and attachable to a typewriter having a movable platen and movable key bars, said device comprising a substantially L-shaped frame having a shallow horizontally extending portion with attaching means thereon for reception of a typewriter thereon and a frame portion extending upwardly from the rear of the horizontally extending frame portion, adjustably variable spacing means movable by character space steps and carried by said upwardly extending portion, means movably mounted on the horizontally extending frame portion for operating said spacing means and positioned beneath the key bars for actuation by direct engagement of any of the key bars upon movement thereof, a driving connection from the spacing means to the typewriter platen, said upwardly extending frame portion lying closely adjacent the rear part of an attached typewriter, holding means for unjustified copy positioned adjacent the upper portion of said upwardly extending frame portion, and means operatively attached to the adjustably variable spacing means and movable to registration with a line end of copy supported in the holding means as an index of adjustment of the variable spacing means.
14. A justifying device operable to different line lengths and attachable to a typewriter having a movable platen and movable type carriers, said device comprising a unitary structure having attaching means for affixing a typewriter thereto and having adjustably variable spacing means movable by character space steps, and connecting means selectively engaging the spacing means to the platen at a desired one of a plurality of positions spaced in the direction of platen movement for lateral displacement of characters on the platen.
15. A justifying device attachable to a typewriter having a movable platen, movable type carriers and operating means therefore, said device comprising a unitary structure having attaching means for affixing a typewriter thereto and having adjustably variable spacing means movable by character space steps, actuating means for the adjustably variable spacing means having a predetermined position on said device and adapted upon attachment of a typewriter to operatively engage the type carrier actuating means for operation thereby, and a driving connection on the device for engagement of the spacing means to the typewriter platen.
16. A justifying device attachable to a typewriter having a movable platen, movable type carriers and operating means therefor, said device comprising a frame having a shallow horizontally extending portion adapted to underlie a typewriter and having attaching means for reception of a typewriter, an upwardly extending frame portion having mounted thereon adjustably variable spacing means movable by character space steps, actuating means for the adjustably variable spacing means adapted upon attachment of a typewriter to the device to operatively engage the type carrier actuating means for operation thereby, and a driving connection on the device for engagement of the spacing means to the typewriter platen.
17. A justifying mechanism comprising a movable platen, means for moving the platen by character space steps, adjustably variable means for varying the length of character space steps and movable to a desired one of a plurality of positions, said adjustably variable means comprising parallel spaced rails, means pivotally supporting said rails on an axis extending perpendicularly to and intermediate said rails, means operatively connecting the adjustably variable means and said platen having engagement with the adjacent faces of said rails, positioning means for the adjustably variable means comprising a body portion movable to a desired one of a plurality of positions, a member pivotally connected to said body portion overlying and engaging opposite faces of said rails, the pivot axis of said pivotally connected member extending perpendicularly to and intermediate said rails.
18. A justifying mechanism operable to different justified line lengths and comprising a movable platen, means for moving the platen by character space steps, adjustably variable means for varying the length of a character space step and movable to a desired one of a plurality of positions having coordinated relationship to the unjustified line shortage and to the justified line length, a copy carrier to hold unjustified copy in predetermined position, means having an operating connection to the adjustably variable means and directly registerable with a random length line of the copy in the copy carrier as an index of adjustment of the adjustably variable means in terms of unjustified line shortage to reproduce that line in justified spacing, and adjustable means for modifying the indexing action of the directly registerable means in accordance with the justified line length.
19. A justifying mechanism operable to different justified line lengths and comprising a movable platen, means for moving the platen by character space steps, adjustably variable means for varying the length of a character space step and movable to a desired one of a plurality of positions having coordinated relationship to the unjustified line shortage and to the justified line length, a copy carrier to hold unjustified copy, indicating means extending toward the copy carrier and movable into registration with unjustified line end, means connecting the indi- 75

cating means and the adjustably variable means for establishing a positioning of the adjustably variable means coordinated to the unjustified line shortage, and adjustable means in said connecting means for modifying the positioning of the adjustably variable means in accordance with the justified line length.

20. A justifying mechanism operable to different justified line lengths and comprising a movable platen, means for moving the platen by character space steps, adjustably variable means for varying the length of a character space step and movable to a desired one of a plurality of positions having coordinated relationship to the unjustified line shortage and to the justified line length, a copy carrier to hold unjustified copy, indicating means extending toward the copy carrier and movable into registration with an unjustified line end, means connecting the indicating means and the adjustably variable means for establishing a positioning of the adjustably variable means coordinated to the unjustified line shortage, and adjustable means in said connecting means for modifying the positioning of the adjustably variable means in accordance with the justified line length, said adjustable means comprising a scale calibrated in terms of character spaces of justified line length, and means for fixing the positioning of the adjustable means at a scale indication of the desired justified line length.

21. A justifying mechanism operable to different line lengths and comprising a movable platen, means for moving the platen by character space steps, adjustably variable means for varying the length of a character space step and movable to a desired one of a plurality of positions having coordinated relationship to the unjustified line shortage and to the justified line length, indicating means movable to establish the positioning of the adjustably variable means, means connecting the indicating means and adjustably variable means for movement of the latter in terms of unjustified line shortage, said connecting means having adjustable means for modifying movement of the adjustably variable means in accordance with the justified line length.

22. A justifying mechanism operable to different line lengths and comprising a movable platen, means for moving the platen by character space steps, adjustably variable means for varying the length of a character space step and movable to a desired one of a plurality of positions having coordinated relationship to the unjustified line shortage and to the justified line length, indicating means movable to establish the positioning of the adjustably variable means, stop means for the indicating means defining stop positions in steps of unjustified character spaces, means connecting the indicating means and adjustably variable means for movement of the latter in terms of unjustified line shortage, said connecting means having adjustable means for modify-

ing movement of the adjustably variable means in accordance with the justified line length.

23. A justifying device operable to different line lengths and comprising a movable platen, means for moving the platen by character space steps, adjustably variable means for varying the length of the character space step and movable to a desired one of a plurality of positionings having coordinated relationship to the unjustified line shortage and to the justified line length, and positioning means for the adjustably variable means comprising a frame, guide means carrying the frame for vertical reciprocable movement, a control shaft, said shaft having an operating connection to the frame and having a control knob thereon for adjustment of the frame to compensate for line shortage, and means adjustably mounted on the frame and movable thereon transversely of the direction of frame travel to a position of adjustment compensating for line length, said adjustably mounted means having an operating connection to said adjustably variable means.

24. A justifying device operable to different line lengths comprising platen moving means movable in character space steps for actuation of a platen, adjustably variable means for effecting a character space step of desired length and adjustable to a desired position coordinated to the line shortage and the desired justified line length, a movable member operatively connected to the adjustably variable means and movable parallel to the direction of travel of the platen moving means to a desired fixed position to establish the line length adjustment of the adjustably variable means, and stop means effective between the platen moving means and the said movable member to arrest movement of the platen moving means.

25. A justifying device operable to give justified line lengths and comprising a movable platen, means for moving the platen by character space steps, adjustably variable means for varying the length of the character space step and movable to a desired one of a plurality of positions having coordinated relationship to the unjustified line shortage and to the justified line length and comprising a track having a pivotal support for swinging movement in one plane, means operable along said track and having connection to the movable platen, and positioning means for the track comprising a reciprocable frame, guide means carrying the frame for rectilinear movement parallel to the plane of movement of the track, means guided by the frame for rectilinear movement parallel to the plane of movement of the track and in a direction transverse to the direction of movement of the frame, and an operating attachment between said last mentioned means and the track and having movement in one direction to adjust the track for unjustified line shortage and having movement in a second direction to adjust the track for justified line length.

EDWARD C. WELLS. 65

CERTIFICATE OF CORRECTION.

Patent No. 2,112,942.

April 5, 1938.

EDWARD C. WELLS.

It is hereby certified that error appears in the printed specification of the above numbered patent requiring correction as follows: Page 1, second column, line 53, for the word "far" read for; page 5, second column, line 12, for "hand hand" read hand; page 7, first column, line 27-28, claim 5, after "calibrated" insert the words with respect to the pivotal support point of the movable member; and that the said Letters Patent should be read with these corrections therein that the same may conform to the record of the case in the Patent Office.

Signed and sealed this 31st day of May, A. D. 1938.

Henry Van Arsdale,
Acting Commissioner of Patents.
